SOCK

Filed Jan. 21, 1926

Inventor
Carl Loven,

Attorney
Horace Barnes.

UNITED STATES PATENT OFFICE.

CARL LOVEN, OF PORTLAND, OREGON.

SOCK.

Application filed January 21, 1926. Serial No. 82,669.

This invention relates to improvements in hosiery.

The object of my invention is the provision of a sock or stocking of simple and practical construction wherein the foot portion is formed along more anatomical lines than hitherto, whereby comfort is afforded to persons having sensitive feet and particularly adapted for the use of small infants or growing children, wherein the bone structure of the foot is of relatively soft and delicate condition.

Further objects and advantages of my invention, and objects relating to details of construction and arrangement of the parts thereof will be readily apparent in the course of the detailed description to follow.

The accompanying drawings illustrate by way of example several forms in which my invention may be embodied, in which Figure 1 is a view in side elevation of a human foot having the sock shown thereon embodying my invention, and Fig. 2 is a partial plan view of Fig. 1.

Referring to said views, wherein similar reference characters indicate like parts in the several views, the reference numeral 1 indicates the foot portion of a sock embodying my invention and 2 the leg portion thereof.

The socks contemplated in my invention are formed of the usual knitted fabric upon the specialized machines usually employed in the knitting of hosiery. In the present example the leg portion and the heel 3 are constructed in the usual or any suitable manner. At or about the instep of the foot, as at 5, upon each side of the sock a plurality of needles are successively added to the machine forming the sock to afford a graduated enlargement in the width of the sock at or about

that portion agreeing with the ball or widest portion of the foot leaving a circular knitted edge 4.

Upon another machine a flat piece 6 of knitted fabric is made having at its base 7 approximately the same number of knitted stitches as are comprised in the circular edge 4 of the sock-foot at or about the middle portion of said piece 16 and toward its outer periphery 8 the number of needles forming said piece are reduced to shape such piece in slightly rounded form, as at 9. The piece 6 is joined to the circular sock portion of the

foot by the operation known as "looping" joining the edges 4 to the base edges 7 of the 55 piece 6 with that portion of said piece 6 in line with the reduced portion 9 thereof upon one side of the sock which will correspond to the inside of the foot of the wearer adjacent the big toe. The sock end is then completed by joining the edges 8 and the side portion thereof 10 in a horizontal line by a sewed or other seam 11. Said toe piece 6 is reversely mounted in the socks of each pair so that they comprise rights and lefts. 65

It will thus be seen that a hygienic sock is produced substantially anatomically correct affording sufficient fullness upon the ball of the foot to accommodate the extra width thereat and thence forward toward the toe-end of the sock retracting sufficiently to adapt itself to the narrowing configuration of the foot across the toes without leaving any undue fullness to form wrinkles and terminating in a toe end slightly rounded but broad 70 enough to accommodate all of the toes in their natural position without restriction and without surplus of material to form wrinkles and folds. 75

From the foregoing description taken in 80 connection with the accompanying drawings the advantages of the construction and application of my improved anatomical sock will be readily apparent, but, while I have described the principle of operation of the 85 invention together with the devices which I now consider the best embodiment thereof, it will be understood that the structures shown are merely illustrative, and that such changes may be made therein as will lie within the 90 scope of the following claims.

Having described my invention, what I claim is:—

1. A sock of the class described consisting in a foot-section of tubular construction terminating adjacent the widest or ball portion of the foot, and a toe portion formed of a flat piece of knitted fabric having its base connected to the said termination of the foot-section and formed with a folded line adapted to lie along the longer side of each foot and closed on its remaining side and toe by a horizontal seam. 95

2. A sock of the class described, consisting in a foot-section of tubular construction terminating adjacent the widest or ball por- 100

tion of the foot having a plurality of knitted stitches successively added at said termination to increase the diameter of such foot-portion, and a toe-portion formed of a flat piece of knitted fabric having its base of equal dimensions as said termination of the foot-section and joined thereto, said toe-portion

being formed at its outer extremity with successively reduced number of knitted stitches and provided with a fold upon one ¹⁰ side of the foot corresponding to the longer side of the foot, with a sewed seam along its remaining side and outer extremity.

CARL LOVEN.
